SAFETY DOOR HANDLE FOR BUS AIR DOORS

Hans Schlesinger, New York, N. Y.

Application June 24, 1938, Serial No. 215,647

8 Claims. (Cl. 74—528)

This invention relates to new and useful improvements in a safety door handle for bus air doors.

The invention has for an object the construction of a safety handle which may be applied to control a bus air door, or doors, and constructed in a manner to prevent accidental opening or closing of the doors.

Heretofore it has been customary to construct buses with a handle for controlling the doors arranged in the vicinity of the steering wheel of the bus. Frequently the operator touches this handle accidentally, causing the opening or closing of the doors.

15 The invention contemplates a construction by which the handle may be locked quickly and efficiently in various positions to open the doors or close the doors, open the door or another only, or other combinations and arrangements.

20 Still further the invention proposes to so arrange the device that it may be easily applied to the equipment in present day buses.

Another object of this invention is to provide an oil splash guard upon the handle in a manner to protect the driver's hand from being splashed with oil.

25 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

30 Fig. 1 is a horizontal sectional view of the front portion of a bus provided with a door control handle and a safety arrangement constructed according to this invention.

Fig. 2 is a perspective view of the air control valve and safety handle construction according to this invention.

35 Fig. 3 is a fragmentary sectional view of Fig. 2.

Fig. 4 is a perspective view of a part of the safety door handle per se.

40 Fig. 5 is a sectional view on the line 5—5 of Fig. 4.

Fig. 6 is a bottom view of Fig. 4.

The safety door handle for bus air doors, according to this invention, includes an annular member 10 adapted to encircle and to be fixedly attached upon a portion of the casing 11 which surrounds the operating stem 12 of an air control for opening and closing the doors 13 of a bus 14. Reference numeral 14^a indicates the steering wheel of the bus. It should be noted

that the air control casing 11 is mounted on the side wall of the bus in the vicinity of the steering wheel 14^a. A handle 15 for controlling the air valve is securely attached to the stem 12 and extends radially thereof. This handle is 5 adapted to be moved by the bus driver for controlling the operation of the doors. The details of this construction will not be given in this specification since it forms no part of the invention and these constructions are generally known 10 at the present time.

A double layer strip of material 16 engages about the annular member 10 and has its ends adjacent each other. A bolt 17 engages through the ends of the said double layer strip 16 for 15 clamping the same fixedly upon the annular member 10. Elements 18 are fixedly clamped between the bottom edge portions of the layers of the strip 16 and form recesses 19 at certain areas for engagement by a holding lever as 20 hereinafter more fully described.

The holding lever for the handle 15 comprises a lever 20 which is pivotally connected with the handle 15 by several lugs 21 and a pintle 22 arranged intermediate the ends of the handle and 25 the lever. The outer end of the lever 20 is urged away from the handle 15 by an expansion spring 23. The inner end of the lever 20 is formed with a reduced portion 20^a adapted to engage selectively the recesses 19, and is guided by projections 30 15 from the handle 15.

The elements 18 must be fixedly arranged in predetermined positions to correctly locate the recesses 19. These recesses 19 should be located at positions so that the handle 15 will be at predetermined positions to open both doors, or selectively open one or the other of the doors of the bus. Buses generally are constructed with a front door and a rear door. Thus a construction is provided for singly or jointly controlling 40 these doors.

A shield 25 extends concentric with the stem 12 and is attached upon the handle 15 by several screws 26. This shield 25 protects the driver's hand from being splashed by oil from the air 45 valve. With present constructions it often happens that escaping air will splash oil on the handle 15. With the shield 25 the oil is prevented from reaching the outer end of the handle which is the portion which is gripped by the 50 driver.

The method of assembly of the device is as follows:

The bolt 17 is loosened; the annular member 10 is fixedly attached upon the casing 11 of the 55

air valve. This may be accomplished by having a drive fit between these parts or by the use of a pin or other fastening element. The double layer strip 16 is then engaged over the annular member 10. While the bolt 17 is still loose the elements 18 may be shifted to various positions along the bottom portion of the double layer strip. It is possible to shift these elements 18 so that the recesses 19 are located at the proper positions for the proper operation of the doors of the vehicle. If desired it is possible to remove one or more of the elements 18 or to add additional elements, as may be desired.

These elements 18 are merely held in position 15 frictionally. The upper ends are formed with split beaded portions 18^a which are engaged in a receiving groove formed in the adjacent faces of the layers of the double strip 16. At the areas where the elements 18 are located, the 20 double strip 16 is formed with a cutout 16^a arranged so that the elements 18 may extend from the top edge of this cutout and extend downwards to a location substantially in the same plane as the wide end portions of the double 25 layer strip.

After the elements have been properly adjusted the bolt 17 is tightened. This serves to rigidly secure the double layer strip of material upon the annular member 10 and to clamp together 30 the layers for frictionally gripping and holding the elements 18. The handle 15 and the control lever 20 are now engaged in place. It is possible to press together the outer ends of the handle 15 and the control lever 20 to pivot the 35 inner end 20^a of the control lever out from one of the recesses 19. Then the handle 15 may be turned as desired. In the new position the lever 20 is released and the spring 23 will urge it into a locking position with the end 20^a re-engaging 40 one of the recesses 19.

While I have illustrated and described the preferred embodiments of my invention, it is to be understood that I do not limit myself to the precise constructions herein disclosed and the right is reserved to all changes and modifications coming within the scope of the invention 45 as defined in the appended claims.

Having thus described my invention, what I claim as new, and desire to secure by United States Letters Patent is:

1. A safety door handle for bus air doors, comprising an annular member adapted to encircle and be fixedly attached on a portion of the casing surrounding the operating stem of an air control 50 for opening and closing bus doors and the like, a double layer strip of material engaging about said annular member and having its ends adjacent each other, a bolt engaging through the ends of said double layer strip for clamping same upon said annular member, elements fixedly clamped between the bottom edge portions of the layers of said strip forming recesses, a handle for attachment on said operating stem, and a lever mounted on said handle and engageable in said recesses for holding the handle in different fixed 55 positions.

2. A safety door handle for bus air doors, comprising an annular member adapted to encircle and be fixedly attached on a portion of the casing 60 surrounding the operating stem of an air control for opening and closing bus doors and the like, a double layer strip of material engaging about said annular member and having its ends adjacent each other, a bolt engaging through the ends of said double layer strip for clamping same 65

upon said annular member, elements fixedly clamped between the bottom edge portions of the layers of said strip forming recesses, a handle for attachment on said operating stem, and a lever mounted on said handle and engageable in 5 said recesses for holding the handle in different fixed positions, said double layer strip having a cutout area along its bottom portion in the vicinity of said elements so that the bottom ends of said elements are substantially in the same 10 plane as the side ends of said double layer strip.

3. A safety door handle for bus air doors, comprising an annular member adapted to encircle and be fixedly attached on a portion of the casing 15 surrounding the operating stem of an air control for opening and closing bus doors and the like, a double layer strip of material engaging about said annular member and having its ends adjacent each other, a bolt engaging through the ends of said double layer strip for clamping same 20 upon said annular member, elements fixedly clamped between the bottom edge portions of the layers of said strip forming recesses, a handle for attachment on said operating stem, and a lever mounted on said handle and engageable in 25 said recesses for holding the handle in different fixed positions, and an oil shield mounted on said handle.

4. A safety door handle for bus air doors, comprising an annular member adapted to encircle 30 and be fixedly attached on a portion of the casing surrounding the operating stem of an air control for opening and closing bus doors and the like, a double layer strip of material engaging about 35 said annular member and having its ends adjacent each other, a bolt engaging through the ends of said double layer of strip for clamping same upon said annular member, elements fixedly clamped between the bottom edge portions of the layers of said strip forming recesses, a handle for attachment on said operating stem, and a lever mounted on said handle and engageable in 40 said recesses for holding the handle in different fixed positions, and an oil shield mounted on said handle, and secured thereon by several screws.

5. A safety door handle for bus air doors, comprising an annular member adapted to encircle and be fixedly attached on a portion of the casing surrounding the operating stem of an air control for opening and closing bus doors and the like, a double layer strip of material engaging about 50 said annular member and having its ends adjacent each other, a bolt engaging through the ends of said double layer strip for clamping same upon said annular member, elements fixedly clamped between the bottom edge portions of the layers of said strip forming recesses, a handle for attachment on said operating stem, and a lever mounted on said handle and engageable in 55 said recesses for holding the handle in different fixed positions, each of said elements having a beaded top edge formed with a split to make the same resilient, and said beaded top edge engaging a groove formed in the adjacent faces of said double layer strip.

6. A safety door handle for bus air doors, comprising an annular member adapted to encircle and be fixedly attached on a portion of the casing surrounding the operating stem of an air control for opening and closing bus doors and the like, a double layer strip of material engaging about 70 said annular member and having its ends adjacent each other, a bolt engaging through the ends of said double layer strip for clamping same upon said annular member, elements fixedly clamped 75

between the bottom edge portions of the layers of said strip forming recesses, a handle for attachment on said operating stem, a lever mounted on said handle and engageable in said recesses 5 for holding the handle in different fixed positions, and a resilient element engaged between the outer ends of said handle and lever for urging the lever into an operative position.

7. A safety door handle for bus air doors, comprising an annular member adapted to encircle and be fixedly attached on a portion of the casing surrounding the operating stem of an air control for opening and closing bus doors and the like, a double layer strip of material engaging about said 10 annular member and having its ends adjacent each other, a bolt engaging through the ends of said double layer strip for clamping same upon said annular member, elements fixedly clamped between the bottom edge portions of the layers of 15 said strip forming recesses, a handle for attachment on said operating stem, a lever mounted on said handle and engageable in said recesses for holding the handle in different fixed positions, and a resilient element engaged between the outer 20 ends of said handle and lever for urging the lever into an operative position, said lever being piv- 25

otally mounted intermediate of its ends upon said handle.

8. A safety door handle for bus air doors, comprising an annular member adapted to encircle and be fixedly attached on a portion of the casing surrounding the operating stem of an air control for opening and closing bus doors and the like, a double layer strip of material engaging about said annular member and having its ends adjacent each other, a bolt engaging through the ends of 5 said double layer strip for clamping same upon said annular member, elements fixedly clamped between the bottom edge portions of the layers of said strip forming recesses, a handle for attachment on said operating stem, a lever mounted 10 on said handle and engageable in said recesses for holding the handle in different fixed positions, and a resilient element engaged between the outer ends of said handle and lever for urging the lever into an operative position, said lever 15 being pivotally mounted intermediate of its ends upon said handle, the handle and the lever being formed with lugs, and a pintle engaging through these lugs for accomplishing the pivotal connections of these parts. 20
